(57) **CLAIM**

The ornamental design for a hood top, as shown and described.

DESCRIPTION

FIG. 1 is perspective view of a hood top according to our new design;

FIG. 2 is top view of the hood top of FIG. 1;

FIG. 3 is a front view of the hood top of FIG. 1;

FIG. 4 is a left side elevational view of the hood top of FIG. 1;

FIG. 5 is a right side elevational view of the hood top of FIG. 1; and,

FIG. 6 is a front cross-sectional view of the hood top of FIG. 1 taken at section line 6-6 in FIG. 2.

The broken lines immediately adjacent the shaded areas, including those disposed around a portion of the periphery of the design as depicted in the figures, represent the bounds of the claimed design while all other broken lines are directed to environment; the broken lines form no part of the claimed design.
